UNITED STATES PATENT OFFICE.

GEORGE WEBSTER, OF PARRAMATTA, NEW SOUTH WALES.

MACHINE FOR EXTRACTING GOLD.

SPECIFICATION forming part of Letters Patent No. 663,375, dated December 4, 1900.

Application filed March 8, 1900. Serial No. 7,922. (No mac.).

To all whom it may concern:

Be it known that I, GEORGE WEBSTER, engineer, a subject of the Queen of Great Britain, residing at Wigram street, Parramatta, 5 in the British Colony of New South Wales, have invented new and useful Improvements in Machines for Extracting Gold from Finely-Divided Metalliferous Materials, of which the following is a specification.

This invention relates to machines for extracting gold from finely-divided metalliferous material—such as battery crushings or tailings, dredgings, or other material containing gold or silver, or both—and the classes of 15 such machine to which it particularly refers are those in which the crushings, tailings, dredgings, or the like are passed with a superabundance of water over or in contact with textile fabric or matting on which the 20 heavier particles are retained.

A machine for extracting gold from finely-divided metalliferous material constructed according to this present invention has a hopper or receiver just above a catching-receptacle with or without riffles, from the upper part of which leads a comparatively long narrow chamber or passage having a fabric-lined bottom and a top or cover closely above said fabric-lined bottom, the whole from the 25 mouth of the hopper to the fabric-lined chamber or passage being water-tight. In the fabric-lined chamber or passage and just at the surface of the fabric are devices by means of which jets of water may be directed 30 adversely to the movement of the material under treatment. Further, the under surface of the cover or top of this fabric-lined chamber or passage may be an amalgamated surface in order to catch, if there be any, float-gold. 35 In order that this invention may be clearly understood, reference will now be made to the drawings herewith, in which—

Figure 1 is a central sectional elevation of a machine such as constructed according to 45 this invention. Fig. 2 is a plan view of the same, the cover of the passage being removed. Figs. 3 and 4 are cross-sections on the lines 3 3 and 4 4, respectively, of Fig. 2.

The comparatively long narrow chamber 50 or passage A rests upon horses or legs a and has at its feed end a hopper B and at its discharge end a receiving-launder or chute c,

leading to waste or otherwise. At the lowermost end of hopper B is opening or orifice B', just a little behind the depression or basin 55 or catching-receptacle C, in which are riffles or catch-plates C' and C² and in the bottom of which is outlet C³, on which is cock C⁴. The passage or chamber A is characterized by the fact of its having a top surface A², 60 as well as a bottom one A', covered by matting A³ or other fabric or similar catchy lining of textile or metallic or other material, and also by the fact that the depth of such chamber or passage is such that no excess 65 volume of water-borne material can pass through it without all particles of any weight being forced onto the matting A³ (where they will be retained) and without all the lighter particles being brought into contact 70 with the surface A², which may be an amalgamated surface, if desired, for the purpose of catching and holding float-gold, if any be present. As an additional precaution, though not an essential to the success of this invention, water-pipes D' and D² are conveyed along the bottom A' in grooves D³, made 75 therein for such purpose. When water is supplied to these pipes D' and D², jets of water are emitted therefrom in a direction 80 (shown by lines d in Fig. 2) adverse to the progress of the material and water through the passage or chamber A. The valves or plugs D⁵ and D⁶ regulate the supply of water, and consequently the force of the jets d. 85

In operation the crushings, dredgings, tailings, &c., are fed in any desired or approved manner to hopper B, to which a regulated superabundance of water is also supplied. The material and water passing through opening B' pass into receptacle C, wherein the heavier particles sink to the bottom, while the remainder endeavors to escape to the passage or chamber A over the riffles C' and C², these catching and retarding the passing away of 95 heavier particles which may have had momentum imparted to them. In the case of tailings being treated this receptacle C is found to catch a comparatively considerable quantity of the mercury wasted in such tailings. The receptacle C is emptied when desired by means of plug or cock C⁴. The material and water which pass the riffles C' and C² then flow over the matting A³, whereon 100

any heavier portions are caught, and finally the remainder discharges into launder *c* and flows to waste. The jets *d* are employed to cause eddies and generally to retard the advance of any heavier particles in the passage or chamber *A*, and so insure that they will settle on the matting *A*³. When the under surface *A*² is silvered or amalgamated, any float-gold in the material passing along chamber or passage *A* is caught and retained and may be cleaned off as may be desired or necessary by withdrawing the cover *A*⁴ from under the bolts *A*⁵.

The most serviceable dimensions of the various parts of a machine for extracting gold from finely-divided metalliferous materials depend particularly upon the class of material to be treated and the quantity and force of water available for same. The main consideration is that the passage or chamber *A* shall be of comparatively small depth, only sufficiently deep, in fact, to allow of a flow of the material and water when the bottom *A'* is set approximately level. The best working of this machine is obtained when the feed into hopper *B* is regular and the operator keenly watches his results. By rough trials he can easily ascertain the quantity of feed, both of material and water, the incline, if any, of the bottom *A'*, and the force and quantity of the jets *d* to retain in use. These rough trials do not entail any more trouble upon a skilled and capable operator than is required in most machines for similar purposes.

Having now particularly described and ascertained the nature of my said invention and in what manner the same is to be performed, I declare that what I claim is—

1. In a machine of the character described, the combination of a comparatively long, shal-

low covered-in passage or chamber, a lining on the bottom of the same, a hopper at one end of said passage or chamber, and a conical catch-receptacle or basin arranged at the discharge end of said hopper and having riffles arranged one in advance of the other, toward the delivery end of said passage or chamber, said catch-receptacle or basin also having an outlet at its bottom controlled by a cock, substantially as set forth. 45

2. In a machine of the character described, the combination of a comparatively long shallow and closely-covered-in passage or chamber, the bottom of which is lined with a matting and the top thereof amalgamated, a hopper arranged at one end thereof, and a conical catch-receptacle or basin arranged at the discharge end of said hopper and having riffles arranged one in advance of the other, toward the delivering end of said passage or chamber, substantially as set forth. 50

3. In a machine of the character described the combination of a comparatively long, shallow covered-in passage or chamber having a lining on its bottom, a hopper at one end thereof, a conical catch-receptacle or basin arranged at the discharge end of said hopper and having riffles arranged one in advance of the other, toward the delivery end of said passage or chamber, and a series of water-pipes arranged to discharge jets of water, oppositely to the flow of material through said passage or chamber, substantially as set forth. 65

In testimony whereof I have signed my name to this specification in the presence of two subscribing witnesses. 75

GEORGE WEBSTER.
